[57] CLAIM

The ornamental design for a wreath storage box, as shown and described.

DESCRIPTION

FIG. 1 is a top left front perspective view of a wreath storage box showing my new design;

FIG. 2 is a front elevational view thereof;

FIG. 3 is a top plan view thereof; the bottom plan view being a mirror image;

FIG. 4 is a left side elevational view thereof; the right side elevational view being a mirror image; and,

FIG. 5 is a rear elevational view thereof.

The broken line showing of environmental features is for illustrative purposes only and forms no part of the claimed design.
